UNITED STATES PATENT OFFICE.

AUGUST F. MILLER, OF SAN FRANCISCO, CALIFORNIA, ASSIGNOR TO SCHMIDT LITHOGRAPH COMPANY, A CORPORATION OF CALIFORNIA.

DISPLAY CARTON.

Application filed February 23, 1922. Serial No. 538,487.

To all whom it may concern:

Be it known that I, AUGUST F. MILLER, a citizen of the United States, residing at San Francisco, in the county of San Francisco, 5 State of California, have invented a new and useful Display Carton, of which the following is a specification, in such full and clear terms as will enable those skilled in the art to construct and use the same.

10 This invention relates to a display carton and an object of the invention is to produce a satisfactory display carton which can be used for the purpose of showing the goods to be sold upon the counter and at the same 15 time producing an artistic effect with a lithograph cover without the necessity of actually lithographing both the inside and the outside of the box, a single lithograph operation providing for the outer decoration of 20 the box when used as a carrying parcel, and the same decorations being made use of when the box cover is open to illuminate the raised cover.

It will be apparent that while the illustration has been applied to a box intended 25 for carrying cans of sardines and shows a plate carrying a number of sardines upon toast, that it is possible to produce any desired picture on the top and to adapt box 30 for service in carrying any kind of merchandise which it may be desired to advertise and sell from the original carton.

Another object of the invention is to provide a corrugated board stiffening to increase 35 the strength of the box and to provide means whereby the key can openers may be conveniently stored while the carton has the packages contained therein under sale.

Another object of the invention is to provide 40 the stiffener of such shape and size as to protect the carton to which this display and reinforcing is applied and may be of any desired type provided it has a cover hinged thereto.

45 Other objects of the invention will appear as the description proceeds.

An embodiment of the invention is shown in the accompanying drawings in which the same reference numeral is applied to the 50 same portion throughout, but I am aware that there may be modifications thereof.

Fig. 1 is a perspective view of the carton with a portion broken away for purposes of illustration as it appears with the cover 55 raised for display purposes.

Fig. 2 is a plan view of the carton cover. Fig. 3 is a vertical sectional view of the carton with the cover raised.

Fig. 4 is a perspective view of the outer corrugated board stiffener, and

Fig. 5 is a perspective view of the inner corrugated board stiffener.

The carton 1 is of any common form open at the top and is provided with a hinged cover made up of the hinged flap 2 folded along the line 3 to produce the front flap 4, 60 tucking flap 5 and display 6.

The display 6 is cut along the line 7 out of the flap 2 in any desired shape, the object being to provide a shape which will be suitable to outline any desired cut to be used for advertising purposes, the present illustration being of a plate with a series of sardine sandwiches.

In order to stiffen the package a rectangular sleeve of fiber board is placed within the carton against the outer edges thereof. This sleeve is indicated at 8 and it has the corrugations extending vertically thereof. This sleeve is put in place within the carton and then the additional fiber board reinforcing which consists of an open ended trough 9 is placed within the same, and it will be observed that the trough 9 consisting of three joined planes of fiber board is 70 taller than the sleeve 8 which leaves a recess between the outer covering of the carton and the inner reinforcing 9 which forms a convenient receptacle for the handle ends of the keys used to open sardine cans.

These keys are inserted in the fiber board sleeve in the same number as the number of sardine cans in the carton, thereby providing a convenient and safe receptacle for the keys. The top being creased along the line 95 3 is raised and folded along that line and the cut at 6 is then pushed out of the back of the cover so that it will stand up above the cover. The flap 5 is then pushed down behind the reinforcing and the cover in that way serves to produce a neat advertising display, though only lithographed on one side the change in position of the cover bringing a sufficiently large advertisement 100 into view to make it satisfactory, while at the same time the cover is not in any way weakened in its connection with the body of the carton.

What I claim is as follows, but various modifications may be made in the construc-

tion shown in the drawings and above particularly described form, within the purview of my invention.

1. A reinforcing for cartons comprising a corrugated board sleeve narrower than the depth of the carton, the corrugations extending vertically and adapted to act as object receptacles, and an additional reinforcing in the carton inside the sleeve substantially of the same height as the carton.
2. A display carton comprising a carton, a cover therefor, a corrugated board rein-

forcing sleeve extending around the inside of the carton and shallower than the carton, the corrugations extending vertically to act as object receptacles, and another corrugated reinforcing member extending inside the sleeve at front and back and across the bottom of the carton.

In testimony whereof I have hereunto set my hand this 6th day of February. A. D. 1922.

AUGUST F. MILLER.
